RAILWAY TRAFFIC CONTROLLING
APPARATUSEarl M. Allen, Swissvale, Pa., assignor to The
Union Switch & Signal Company, Swissvale,
Pa., a corporation of Pennsylvania

Application March 19, 1935, Serial No. 11,808

23 Claims. (Cl. 246—160)

My invention relates to railway traffic controlling apparatus, and has particular reference to approach locking apparatus for locking a track switch against operation when a signal governing the movement of traffic over the switch has been cleared and also under certain traffic conditions for a selected time interval after the signal is manually restored to stop. More specifically, my invention relates to the group release of approach locking, in which a single time releasing device is employed with different groups of signals, and in respect to this feature my invention is an improvement upon that disclosed and claimed in a copending application Serial No. 11,807, filed this day by Charles W. Bell, for Interlocking control apparatus.

One object of my invention is to provide an arrangement in which a single time releasing device or group of devices is employed to release the locking for all of the signals of an interlocking plant, the time interval imposed upon the release of the locking being relatively long or relatively short, depending upon whether the signal put to stop is one for governing high speed or slow speed traffic.

Another object of my invention is to arrange the time releasing device so that it is self-checking, by the provision of selecting apparatus which prevents the control of the time releasing device by a signal to release the locking associated therewith except when the time releasing device is in its normal inactive condition.

A further object of my invention resides in the provision of a thermal time releasing device which is so arranged that it can be set into operation only when in its normal cooled condition, and which has contacts closed respectively at the beginning and at the end of a measured time interval, these contacts being included in circuits so controlled that the time delay will not be defeated if they become connected together.

Other objects, purposes and features of my invention will appear as the description progresses.

I will describe one form of apparatus embodying my invention, and will then point out the novel features thereof in claims.

Referring to the accompanying drawing, the track plan at the top represents a stretch of double track railroad comprising the territory controlled by an interlocking plant, each track being indicated by a single line. The movement of traffic over the lower track is normally from left to right and over the upper track is from right to left, the two tracks being connected by a

crossover comprising switches 1 and 1A, which are controlled by power operated switch machines 1SM and 1ASM, respectively, of the usual type. The lower track includes a switch section 1T containing switch 1 and two approach sections A1T and 2T, while the upper track includes a switch section 3T containing switch 1A and two corresponding approach sections A3T and 4T. Each track section is provided with the usual closed track circuit including a normally energized track relay. The track relays for the upper track, being duplicates of those for the lower track, have been omitted, while the track circuits for the relays for the lower track, which are relays A1TR, 1TR and 2TR, have been indicated diagrammatically by dotted line connections from the relays to the respective track sections of the track plan.

The movement of traffic into section 1T in the normal direction is governed by a signal R2 comprising a high speed arm a which may be cleared to indicate "caution" or "proceed" in accordance with traffic conditions in advance when section 1T is unoccupied and switch 1 is normal, and an auxiliary slow speed arm, or "call-on" signal c, which may be cleared to permit a train to enter section 1T at low speed when switch 1 is reversed or section 1T is occupied by a preceding train. The movement of traffic into section 1T in the opposite direction is governed by the slow speed signal L2. A distant signal R2D for governing traffic approaching section 1T is located a suitable distance in the rear of signal R2, and it is to be understood that in accordance with the usual practice signal R2D is cleared to indicate "proceed" only when arm a of signal R2 has been cleared to indicate "caution" or "proceed", and section A1T is unoccupied.

The arms a and c of signal R2 are controlled by the signal relays RA2H and RC2H, respectively, and signal L2 is controlled by a signal relay L2H. The local signal circuits are not shown in detail, but it is to be understood that each signal arm will be cleared when the corresponding signal relay is energized, and will indicate stop when its signal relay is deenergized. Relays RA2H and RC2H are selectively controlled, through the medium of a lever repeating relay R2VR and a stick relay C2VS by a manually operable signal lever R2V, which is shown in the drawing in its normal position, that is, in the position to which it is moved to cause signal R2 to indicate stop. Lever R2V is a three-position lever and may be moved to the right to clear arm a or to the left to clear arm c of signal R2.

Signal relay L2H is controlled by the lever L2V through the medium of a lever repeating relay L2VR, lever L2V being a two-position lever which may be moved to the left to clear signal L2 or 5 to the normal position, as shown, to cause signal L2 to indicate stop.

The movement of traffic over the upper track is governed by the signals R4, L4 and L4D, which are similar to and are controlled in the same 10 manner as the corresponding signals for the lower track. To simplify the drawing, the control circuits for these signals have been omitted, only the relays L4VR and C4VS being shown, these relays controlling the signal L4 in the same way 15 as relays R2VR and C2VS and control signal R2.

The switch machines 1SM and 1ASM for operating switches 1 and 1A have the usual circuit controllers for controlling indication relays, such 20 as 1NKR and 1RKR, for selecting the signals in accordance with the positions of the switches. It is to be understood that relay 1NKR is energized only when switches 1 and 1A are both closed and locked normal, so as to permit parallel train movements on the two main tracks, and that 25 relay 1RKR is energized only when the switches are both closed and locked reverse to permit train movements from one main track to the other.

The switch machines 1SM and 1ASM are controlled by polarized switch control relays 1WR and 1AWR, respectively, by circuits not shown in detail, but which are of the usual type as illustrated for example in the Willard Patent No. 1,380,452, issued June 7, 1921. Relays 1WR and 35 1AWR are controlled over a polarized switch control circuit by a manually operable switch lever 1V. This circuit, shown at the bottom of the drawing, includes contacts 24 to 29, inclusive, of approach locking relays and of the track relays 40 for the switch sections. The purpose of these contacts is to at times lock the switch against operation by lever 1V. It is obvious that the operation of the switch is prevented when any of these contacts is open, that is, when any approach locking relay is deenergized or when either 45 switch section is occupied.

An approach locking relay is provided for each signal governing the movement of traffic into a switch section, these relays being identified by 50 the reference MR with a prefix corresponding to the designation of the associated signal. Each approach locking relay is a stick relay, and is released to lock the switch when the associated signal is cleared, but becomes energized when the 55 signal is restored to stop only if certain conditions are fulfilled. Thus for example, considering relay R2MR, if signal R2 is put to stop by a train entering section 1T, a pickup circuit for relay R2MR will be closed over back contact 5 of relay R2MR when the train passes the signal. If signal R2 is put to stop manually, and there is 60 no train approaching so that section 1T is unoccupied, a pickup circuit for relay R2MR will be closed over front contact 6 of relay 1TR, but if this contact is open, relay R2MR will remain deenergized and a circuit will be closed over its back contact 7 to pick up a selector relay R2S to set certain time measuring apparatus into operation, as hereinafter described, to pick up relay 65 R2MR at the end of a measured time interval, this time interval being controlled by a stick relay C2VS in the manner disclosed and claimed in a copending application of Earl M. Allen and Henry S. Young, Serial No. 2,076, filed Jan. 16, 70 75 1935, for Railway traffic controlling apparatus,

so that the time will be relatively long or short, depending on whether arm a or arm c has been put to stop. Relay R2MR when picked up is held by a stick circuit including its front contact 7 until signal R2 is again cleared. Relay L2MR is 5 similarly controlled by signal L2 and by the track relays for sections 1T and 2T, except that since signal L2 is a slow speed signal only the short time element is imposed when selector relay L2S 10 becomes energized. The circuits for the approach locking relays L2MR and R2MR associated with signals L4 and R4, respectively, are exactly like those for relays R2MR and L2MR, and are therefore omitted from the drawing, and it is to be understood that the selector relays 15 L4S and R4S are associated with the locking relays for the upper track in the same way relays R2S and L2S are associated with those of the lower track.

The selector relays S associated with the approach locking relays MR control time measuring means including a time element relay TE for providing a long time element, and a thermal relay TH for providing a short time element for 20 at times delaying the release of the locking. The time element relay TE may be of any suitable type, and as herein disclosed is to be understood to be arranged to open a checking contact 71 when it becomes energized, and to then close a contact, such as contact 8 included in one of the circuits for relay R2MR, after an adjustable time interval which in practice is usually from 25 one to four minutes. One form of relay which may be employed in this connection is disclosed 30 in a patent for Electrical relays, No. 1,966,965, issued July 17, 1934, to B. Lazich and H. E. Ashworth. The thermal relay TH may be of the usual type comprising a contact member 9 formed of a bimetallic or thermostat strip forming a 35 heat responsive member with a coil of resistance wire wound thereon or adjacent thereto, and the contact 9 occupies the position shown in the drawing in which it connects with a fixed back contact only when the heat responsive member is in its normal cooled condition. When the coil 40 is energized, contact 9 becomes deflected, and connects with a fixed front contact to pick up a stick relay THS at the end of a measured time 45 interval, whereupon the coil of the relay TH will become deenergized allowing the heat responsive member to cool for a measured time interval, when a checking relay NT becomes energized. Each approach locking relay MR associated with a slow speed signal has a pickup circuit including front contacts of the stick relay 50 THS and of the checking relay NT, and also including a front contact of its respective selector relay, such as relay R2S, which circuit becomes closed when the selector relay has been energized and the thermal relay TH has been operated 55 through a cycle of heating and cooling and has returned to its normal condition. Each relay MR associated with a high speed signal also has a pickup circuit including front contacts of the time element relay TE and of its selector relay 60 such as relay R2S.

The circuits for controlling the selector relays also include contacts of a slow acting checking relay NTP, which is energized only when all selector relays S are deenergized and relays TE, 70 NT and THS are in their normal condition, these circuits being so arranged that no selector relay can become energized unless relay NTP is energized.

In order to simplify the drawing, I have shown 75

relay contacts which in some instances are not adjacent the respective relays which operate them, but in each case such contacts bear the reference characters identifying the respective relay as well as a number identifying the contact. Thus, for example, one branch of the pickup circuit for relay R2MR includes back contact 5 of track relay 1TR. The corresponding circuit for relay L2MR also includes a back contact 10 of the 1TR relay, contact 10 bearing the reference 1TR to indicate the relay which operates it. I have also, in the accompanying drawing, not shown the source of current for energizing the various relays but have shown in lieu thereof only the terminals of the source which I have identified by the references B and C to designate the supply and common terminals of the source, respectively.

I will now describe the operation of my apparatus in connection with an assumed train movement from left to right over the lower track. Considering the apparatus to be in its normal condition as shown in the drawing, a circuit may be traced from terminal B, contact 11, which is closed when signal R2D indicates "caution" or "stop", back contacts 12 and 13 of signal relays RC2H and RA2H, front contact 6 of relay A1TR, relay R2MR to the other terminal C of the source of current. Relay R2MR becomes energized over this circuit and closes its stick contact 7 bridging contact 6, so that relay R2MR will remain energized as long as signal R2 remains at stop.

To clear arm a of signal R2 for an approaching high speed train, the operator moves lever R2V to the right, closing a circuit which may be traced from terminal B, lever contact 14, relay R2VR to terminal C. Since switches 1 and 1A are normal the normal indication circuit, which may be traced from terminal B, contacts 15 and 15A of the switch circuit controllers, relay 1NKR to terminal C is closed, so that relay 1NKR is energized. Assuming that signal L2 is at stop and that its approach locking relay L2MR is energized, the circuit for relay RA2H will be closed, and may be traced from terminal B, front contact 16 of relay L2MR, back contact 17 of relay L2VR, front contact 18 of relay 1NKR, front contact 19 of relay R2VR, back contact 20 of relay C2VS, front contacts 21 and 22 of relays 1TR and 1NKR, relay RA2H to terminal C. Relay RA2H thus becomes energized to clear arm a of signal R2 and to open its back contact 13 to deenergize relay R2MR which relay, upon releasing, opens contact 24 in the control circuit for relays 1WR and 1AWR to lock switches 1 and 1A against operation.

When the approaching train passes signal R2, relay 1TR releases, opening contact 21 to deenergize relay RA2H to put the signal to stop and to close back contact 13 in the pickup circuit of relay R2MR, which circuit is completed over back contact 5 of relay 1TR so that relay R2MR becomes energized. The switch, however, remains locked because contact 26 of relay 1TR in the switch control circuit is now open. When the train leaves section 1T, relay 1TR again picks up to complete the switch control circuit, which may be traced from terminal B, contacts 23 to 29, inclusive, relays 1WR, 1AWR, contact 30 to terminal C. Contacts 23 and 30 constitute a pole-changer whereby relays 1WR and 1AWR may be energized in the direction corresponding to the position of the lever 1V to control the circuits for the switch machines 1SM and 1ASM to operate the switches to normal when lever 1V is moved

to its left-hand position as shown and to reverse the switches when lever 1V is moved to the right.

Assume now that switches 1 and 1A have been reversed, a circuit will be closed from terminal B, contacts 31 and 31A of the switch circuit controllers, relay 1RKR to terminal C so that relay 1RKR becomes energized. The operator may now clear arm a of signal R2 to permit a slow speed movement over the switches by moving lever R2V to the left to close a circuit which may be traced from terminal B, contact 32 of lever R2V, front contact 33 of relay R2MR, relay C2VS to terminal C. Relay C2VS therefore becomes energized and since contact 14 is also closed when lever R2V is moved to the left, relay R2VR is energized and a circuit is closed which may be traced from terminal B, back contact 34 of relay C4VS, front contact 35 of relay L4MR, back contact 36 of relay L4VR, contact 37 of relay 1RKR, front contacts 19 and 29 of relays R2VR and C2VS, relay RC2H to terminal C. Relay RC2H therefore becomes energized to clear arm a of signal R2, and to open contact 12 to release relay R2MR to lock the switches. The latter relay, upon releasing, opens the pickup circuit of relay C2VS, which however, does not release, being now energized over its stick circuit which may be traced from terminal B, front contact 38 of relay C2VS, contact 39 of lever R2V, back contact 33 of relay R2MR, relay C2VS to terminal C. Relay RC2H is controlled independently of track relay 1TR so that arm a will not go to stop when the approaching train enters section 1T and therefore to release the locking in this instance, lever R2V must be restored to its normal position while section 1T is occupied.

Assume now that arm a of signal R2 has been cleared but that it is restored to stop by returning lever R2V to normal when a train is approaching and is occupying section A1T. Relays R2VR and RA2H will then release but relay R2MR will not pick up because contact 6 in its pickup circuit is open, due to the presence of the approaching train. Assuming the time element devices are in their normal condition a circuit is closed which may be traced from terminal B, back contacts 40 to 43, inclusive, of relays L4S, R4S, L2S and R2S, back contact 41 of time element relay TE, front contact 44 of relay NT, back contact 45 of relay THS, checking relay NTP to terminal C. A circuit is now also closed from terminal B, contacts 11, 12 and 13, back contact 7, front contact 46 of relay NTP, relay R2S to terminal C. Relay R2S picks up and establishes its stick circuit including contact 47 and opens contact 43 to release relay NTP, which relay now opens contact 46 and also the similar contacts 48, 49 and 50 in the pickup circuits of the other selector relays. A circuit is now closed from terminal B, contact 51 of relay R2S, back contact 52 of relay C2VS, time element relay TE to terminal C. Relay TE upon becoming energized, opens contact 71 and at the end of a measured time interval closes its contact 8 to complete the branch of the pickup circuit for relay R2MR which includes that contact and front contact 53 of relay R2S so that relay R2MR picks up, closing its stick circuit over front contact 7. Back contact 7 in the stick circuit of relay R2S now being open, this relay releases and deenergizes relay TE and upon the return of relay TE to its normal condition, contact 71 closes so that relay NTP again picks up. The time measuring apparatus is now in its normal condition and if any of the other signals has been put to stop during the time in which relay NTP was re-

leased, their selector relays may now become energized to effect the pick up of the associated locking relays.

I will now assume that arm *c* of signal *R2* has been cleared instead of arm *a*, and that arm *c* is then put to stop, by manually returning lever *R2V* to normal while the approach section *A1T* is occupied. When the signal returns to stop, back contact *12* of relay *RC2H* closes to complete the circuit over back contact *7* of relay *R2MR* and front contact *46* of relay *NTP* to pick up relay *R2S* as already described, but in this instance, since the stick relay *C2VS* is energized, a circuit is closed from terminal *B*, front contacts *51* and *52* of relays *R2S* and *C2VS*, back contact *54* of the stick relay *THS*, through the heating element of the thermal relay *TH* to terminal *C*. In a short period of time back contact *9* of relay *TH* will become deflected to open the circuit from terminal *B*, through contact *9* and the fixed back contact of relay *TH*, relay *NT* to terminal *C*, thereby releasing relay *NT* to open contact *44* and to close contact *56*. After relay *TH* has been heated for a measured time interval, a circuit is closed from terminal *B*, front contact *9*, back contact *56* of relay *NT*, relay *THS* to terminal *C*. Relay *THS* picks up, completing its stick circuit from terminal *B* front contacts *51*, *52* and *54*, relay *THS* to terminal *C*. The opening of back contact *54* deenergizes relay *TH*, and after a predetermined cooling period contact *9* will assume its original position and relay *NT* will again pick up to complete the branch of the pickup circuit for relay *R2MR* which includes contacts *51*, *58* and *59* of relays *NT*, *THS* and *C2VS*, respectively, and contact *53* of relay *R2S*. Relay *R2MR* thereupon picks up, relays *R2S* and *THS* release in turn, and relay *NTP* picks up when back contact *45* of relay *THS* closes. Relay *C2VS* becomes de-energized by the opening of back contact *33* of relay *R2MR* and releases.

If, now the operator desires to reverse the direction of traffic and to clear signal *L2*, he will move lever *L2V* to the left, completing a circuit from terminal *B*, contact *60* of lever *L2V*, relay *L2VR* to terminal *C*, and if relay *R2MR* has been picked up and relay *C2VS* released, as described in the preceding paragraph, a circuit is closed from terminal *B*, back contact *61* of relay *C2VS*, front contact *62* of relay *R2MR*, back contact *19* of relay *R2VR*, front contact *18* of relay *1NKR*, front contact *17* of relay *L2VR*, relay *L2H* to terminal *C*, so that relay *L2H* becomes energized to clear signal *L2* and opens its back contact *62* to release relay *L2MR*. If, now signal *L2H* is restored manually to stop while approach section *2T* is occupied and front contact *63* of relay *2TR* in the pickup circuit of relay *L2MR* is open, a circuit will be completed from terminal *B*, back contacts *62* and *64* of relays *L2H* and *L2MR*, front contact *48* of relay *NTP*, relay *L2S* to terminal *C*. Relay *L2S* picks up, closing contact *65* to complete its stick circuit, opening contact *42* to release relay *NTP* and closing contact *66* to energize thermal relay *TH*, and also closing contact *67* in the branch of pickup circuit for relay *L2MR* which includes contacts *68* and *69* of relays *THS* and *NT*. These relays function in the same manner as when controlled by relay *R2S* as already described, and relay *L2MR* becomes energized when relay *NT* picks up to close contact *69* at the end of the short time interval.

As hereinbefore pointed out, the control apparatus for the upper track is similar to that for the lower track. Relays *R4S* and *L4S* together

with relay *C4VS* control the time element device through the medium of contacts *40*, *41*, *55*, *70* and *72* in the same manner as relays *R2S* and *L2S*. It will be clear from the drawing that any desired number of additional selector relays may be included in the circuits provided and that each such relay may have a back contact such as contact *40* in the circuit of relay *NTP* and a front contact such as contact *70* for energizing the time element device or devices and that but one time element relay and but one thermal relay are required, irrespective of the size of the interlocking plant. It is also evident that the time element devices are self-checking and that since the circuit for relay *NTP* controlling the pickup of the selector relays includes contacts *44*, *45* and *71*, it is impossible for any selector relay to become energized after either time element device has started to measure a time interval until the device has again returned to its normal condition. Furthermore, if the front and back contact *9* of the thermal relay *TH* should stick together, relay *NT* would not release and therefore relay *THS* would not pick up and the nullification of the time element which would otherwise occur will not take place.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a selector relay, an electro-responsive device controlled by the selector relay, a thermal relay operable through a cycle comprising a heating period and a cooling period, a checking relay energized only when the thermal relay is in its normal condition, means preventing the selector relay from becoming energized unless the checking relay is energized, means effective when the selector relay is energized to operate the thermal relay through its cycle, and means controlling said electro-responsive device upon the return of the thermal relay to its normal condition.

2. In combination, a selector relay, an electro-responsive device controlled by the selector relay, a thermal relay operable through a cycle comprising a heating period and a cooling period, a checking relay energized only when the thermal relay is in its normal condition, means effective when the selector relay is energized to operate the thermal relay through its cycle, means preventing the return of the thermal relay to its normal condition unless the checking relay becomes deenergized, and means controlled by the selector relay for controlling said electro-responsive device when the checking relay again becomes energized.

3. In combination, a selector relay, an electro-responsive device controlled by the selector relay, a thermal relay operable through a cycle comprising a heating period and a cooling period, a checking relay energized only when the thermal relay is in its normal condition, a stick relay which becomes energized at the end of the heating period of the thermal relay, and means effective when the selector relay is energized to operate the thermal relay through its cycle and to control said electro-responsive device when both the checking relay and the stick relay are energized.

4. In combination, a selector contact, an electro-responsive device, a thermal relay, a checking relay, a stick relay, an energizing circuit for the thermal relay including the selector contact and a back contact of the stick relay, a pickup circuit for the stick relay including a back contact of the checking relay and a contact closed when the thermal relay is in its heated condition, a stick circuit for the stick relay including its own front contact and the selector contact, a circuit for the checking relay closed only when the thermal relay is in its normal cooled condition, and an energizing circuit for said electro-responsive device including front contacts of the checking relay and of the stick relay. 5
5. In combination, a control contact, a selector relay controlled by said contact, an electro-responsive device, a thermal relay, a checking relay, a stick relay, a circuit for the thermal relay including a front contact of the selector relay and a back contact of the stick relay, a pickup circuit for the selector relay including said control contact and a front contact of the checking relay, a holding circuit for the selector relay including said control contact and a contact closed only when the electro-responsive device is deenergized, a pickup circuit for the stick relay including a contact closed only when the thermal relay is in its heated condition, a stick circuit for the stick relay including a front contact of the selector relay, a circuit for the checking relay closed only when the thermal relay is in its normal cooled condition, a pickup circuit for the electro-responsive device including front contacts of the stick relay and of the checking relay, and a holding circuit for the electro-responsive device including said control contact and a contact closed when the electro-responsive device is energized. 10
6. In combination, an electro-responsive device, a heat responsive element, a heater for heating said element, a first and a second stick relay, a checking relay, a control contact, pickup and stick circuits for the first stick relay each including said control contact, the pickup circuit also including a contact closed only when the checking relay is energized, an energizing circuit for the heater closed only when the first stick relay is picked up and the second stick relay is released, a circuit for the checking relay closed only when the heater is in its normal cooled condition, a pickup circuit for the second stick relay closed only when the heater is in its heated condition, a stick circuit for the second stick relay controlled by a front contact of the first stick relay, and a circuit for energizing said electro-responsive device including front contacts of the checking relay and of both said stick relays. 15
7. In combination, an electro-responsive device, a stick relay, a heat responsive element, a heater for heating said element, a checking relay, a control contact, an energizing circuit for said heater closed in response to the closing of the control contact provided the electro-responsive device and the stick relay are deenergized, a pickup circuit for the stick relay closed only when the checking relay is deenergized and the heat responsive element is in its heated condition, a stick circuit for the stick relay controlled by the control contact and closed only when the electro-responsive device is deenergized, a circuit for the checking relay closed only when the heat responsive element is in its normal cooled condition, a pickup circuit for the electro-responsive device closed only when the stick relay and the checking relay are energized, and a holding circuit for the electro-responsive device including the control contact. 20
8. In combination, a selector relay, an electro-responsive device, time element means, a checking relay energized only when the time element device is in its normal condition, means preventing the energization of the selector relay unless the checking relay is energized, means effective when the selector relay is energized to operate the time element means for a measured time interval and to then return it to its normal condition, and a circuit controlled by front contacts of the selector relay and of the checking relay for controlling said electro-responsive device upon the return of said time element means to its normal condition. 25
9. In combination, a selector relay, an electro-responsive device, time element means, a checking relay, means energizing said checking relay only when the time element device is in its normal condition, a stick relay, means effective when the selector relay is energized to operate said time element device, means controlled by said time element device when operated to pick up said stick relay at the end of a measured time interval only if said checking relay releases, means retaining said stick relay energized until the selector relay releases, means effective when the stick relay becomes energized for restoring the time element device to its normal condition, means effective when both the stick relay and the checking relay are energized for operating said electro-responsive device, and means responsive to the operation of the electro-responsive device for releasing the selector relay. 30
10. In combination, an electro-responsive device, a time element device, a stick relay, a checking relay, a manually controllable contact, an energizing circuit for said time element device including said manually controllable contact and a back contact of the stick relay, a pickup circuit for the stick relay including a back contact of the checking relay and a contact closed when the time element device has been energized for a measured time interval, a stick circuit for the stick relay including said manually controllable contact, a circuit for the checking relay closed only when the time element device has been deenergized for a measured time interval, and an energizing circuit for the electro-responsive device including front contacts of the stick relay and of the checking relay. 35
11. In combination, an electro-responsive device, a time element device, a stick relay, a checking relay, a manually controllable contact, an energizing circuit for said time element device including said manually controllable contact and a back contact of the stick relay, means preventing the closing of said circuit unless the checking relay is energized, a pickup circuit for the stick relay closed only when the time element device has been energized for a measured time interval, a stick circuit for the stick relay including said manually controllable contact, a circuit for the checking relay closed only when the time element device has been deenergized for a measured time interval, and an energizing circuit for said electro-responsive device including front contacts of the stick relay and of the checking relay. 40
12. In combination, a plurality of selector relays, an electro-responsive device for each selector relay, a normally deenergized time element device, means preventing the energization of any selector relay except when said time element de- 45
- 50
- 55
- 60
- 65
- 70
- 75

vice is in its normal condition, means effective when any selector relay is energized to operate the time element device, means retaining such relay energized while the time element device is 5 in operation, means controlled by the time element device for operating the electro-responsive device associated with the energized selector relay when it has operated for a measured time interval, and means controlled by the electro- 10 responsive device when operated for restoring the time element device to normal.

13. In combination, a plurality of selector relays, an electro-responsive device for each selector relay, a normally deenergized time element 15 device, means preventing the energization of any selector relay except when said time element device is in its normal condition, means effective when any selector relay is energized to operate the time element device through a cycle, said 20 time element device returning to its normal condition at the end of a measured time interval, and means controlled by the energized selector relay for operating the associated electro-responsive device upon the return of the time element 25 device to its normal condition.

14. In combination, a plurality of selector relays, an electro-responsive device for each selector relay, a time element device, a checking relay, a circuit for energizing said checking relay 30 closed only when all of the selector relays are deenergized and the time element device is in its normal condition, means preventing the energization of any selector relay except when the checking relay is energized, means effective when 35 any selector relay is energized to operate the time element device, and means controlled by the energized selector relay for operating the corresponding electro-responsive device at the end of a predetermined time interval measured by said time element device.

40 15. In combination, a plurality of selector relays, an electro-responsive device for each selector relay, a thermal relay operable through a cycle comprising a heating period and a cooling period, means preventing the energization of any 45 selector relay except when said thermal relay is in its normal cooled condition, means effective when any selector relay is energized to operate the thermal relay through said cycle, and means controlled by the energized selector relay for 50 operating the associated electro-responsive device upon the return of said thermal relay to its normal condition.

55 16. In an interlocking system for railroads, a railway track switch, a plurality of signals for governing the movement of traffic over said switch, a locking relay for each signal which when deenergized prevents operation of the switch, a selector relay for each signal, a thermal relay operable through a cycle comprising a heating period and a cooling period, means effective when a signal is manually put to stop under certain traffic conditions to energize the corresponding selector relay provided said thermal 65 relay is in its normal cooled condition, means effective when a selector relay is energized to operate said thermal relay through said cycle, and means controlled by the energized selector relay for energizing the corresponding locking relay upon the return of said thermal relay to its normal condition.

70 17. In an interlocking system for railroads, a railway track switch, a plurality of signals for governing the movement of traffic over said switch, a locking relay for each signal which

when deenergized prevents operation of the switch, a selector relay for each signal, a time element device, a checking relay, a circuit for energizing said checking relay closed only when all of the selector relays are deenergized and the 5 time element device is in its normal condition, means effective when a signal is manually put to stop under certain traffic conditions to energize the corresponding selector relay provided said checking relay is energized, means effective 10 when any selector relay is energized to operate the time element device, and means controlled by the energized selector relay for energizing the corresponding locking relay at the end of a measured time interval.

15 18. In an interlocking system for railroads, a railway track switch, a plurality of signals for governing the movement of traffic over said switch, a locking relay for each signal which when deenergized prevents operation of the 20 switch, a selector relay for each signal, a time element device, means effective when a signal is manually put to stop under certain traffic conditions to energize the corresponding selector relay provided said time element device is in its 25 normal deenergized condition, means effective when any selector relay is energized to operate the time element device, means retaining such selector relay energized while the time element device is in operation, means controlled by the 30 time element device for energizing the locking relay associated with the energized selector relay when it has been operated for a measured time interval, means effective when such locking relay becomes energized to release the selector relay, and means effective when the selector relay releases to restore the time element device to its 35 normal condition.

19. In an interlocking system for railroads, a railway track switch, a plurality of signals for 40 governing the movement of traffic over said switch, locking means for each signal effective when such signal has been cleared to prevent operation of the switch, means for delaying the release of the locking when a signal is put to 45 stop under certain traffic conditions comprising a thermal relay operable through a cycle comprising a heating period and a cooling period, means operating said thermal relay, provided it is in its normal cooled condition, when a signal 50 is put to stop under said certain traffic conditions, and means effective to release the locking associated with said signal only upon the return of said thermal relay to its normal condition.

55 20. In an interlocking system for railroads, a railway track switch, a signal for governing the movement of traffic over the switch, a locking relay which when deenergized prevents operation of the switch, a time element device which becomes energized when the signal is put to stop 60 provided said locking relay is deenergized and said time element device is in its normal condition, a stick relay, means for energizing said stick relay when the time element device has been energized for a measured time interval, 65 means controlled by the stick relay when energized for deenergizing said time element device and for then energizing said locking relay upon the return of said element device to its normal condition, and means maintaining said locking 70 relay energized until said signal is again cleared.

75 21. In an interlocking system for railroads, a railway track switch, a signal for governing the movement of traffic over the switch, a locking relay which becomes deenergized when the signal

- is cleared and which when deenergized prevents operation of the switch, a time measuring device, means operating the time measuring device when the signal is put to stop provided the locking relay 5 remains deenergized, a stick relay, means energizing the stick relay at the end of a measured time interval after the time measuring device is operated, means controlled by the stick relay when energized to return the time measuring device to its normal condition, means effective when the time measuring device returns to its normal condition to energize the locking relay, and means for maintaining the locking relay energized until the signal is again cleared. 10
- 15 22. In an interlocking system for railroads, a railway track switch, a plurality of signals for governing the movement of traffic over the switch, a locking relay for each signal deenergized when the signal is cleared and effective 20 when deenergized to prevent operation of the switch, a selector relay for each locking relay, a time measuring device, means effective when any signal is put to stop to energize the corresponding selector relay as long as the associated locking 25 relay remains deenergized, means controlled by each selector relay when energized for operating said time element device, means controlled by the time element device when operated to ener-

gize the locking relay corresponding to the energized selector relay at the end of a measured time interval, thereby releasing such selector relay, means maintaining such locking relay energized until the corresponding signal is again cleared, and means preventing the energization of any selector relay except when all selector relays are deenergized and said time element device is in its normal condition. 5

23. In an interlocking system for railroads, a plurality of railway track switches, a high speed signal and a slow speed signal for governing the movement of traffic over each switch, locking means for each signal rendered effective when the signal has been cleared to prevent operation 10 of the switch, a time measuring device, means effective when a signal is put to stop under certain traffic conditions to energize the time measuring device provided said device is in its normal condition, means controlled by the time 15 measuring device for selectively releasing at the end of a measured time interval the locking means associated with such signal, and selecting means for causing said time interval to be relatively long when a high speed signal has been 20 put to stop and relatively short when a slow speed signal has been put to stop. 25
